FILING DEVICE

Harry A. Wardy, Los Angeles, Calif.

Application August 19, 1944, Serial No. 550,135

4 Claims. (Cl. 129—16)

1

This invention relates to devices for handling and containing ledger sheets, charge slips, statements, cards and papers and documents of various kinds. A general object of this invention is to provide a device of this nature which facilitates the ready sorting, filing and withdrawal of the papers.

Another object of this invention is to provide a filing device of the character referred to that may be easily enlarged or reduced in capacity at will.

Another object of this invention is to provide a filing device in which the papers are contained in series of stepped pockets or receptacles each individually accessible and each provided with suitable individual identifying indicia.

Another object of this invention is to provide a device of the character referred to in which each series of paper containing pockets is made up of a number of boards, sheets or cards arranged one behind the other with their lower edges connected and supported in stepped relation by means which provide bottoms for the paper receiving spaces between the cards, said bottoms being spaced one above the other in an upward and rearward progression so that the papers in the spaces are supported in stepped order for easy access and for ready visibility.

Another object of this invention is to provide a filing device of the character mentioned embodying simple, effective means for securing additional boards or cards to the pocket forming assemblies so that said assemblies may be increased in extent as conditions may require.

Another object of this invention is to provide a device of the character mentioned embodying novel and effective means for separating or spreading the pocket forming assemblies and for freeing their individual cards or boards for easy manual spreading, rendering the identifying means of the assemblies and their individual cards readily visible and to facilitate the removal, sorting in and inspection of the contents or papers.

Another object of this invention is to provide a filing device of the character mentioned in which the pocket assemblies are supported at their opposite sides and between their upper and lower ends and the means for separating or spreading the pocket assemblies operates to exert a rearward force or compressing force on the lower portions of a number of such assemblies to cause the upper portions of the assemblies to spread apart.

Another object of this invention is to provide a filing device of the character referred to in

2

which the card or pocket assemblies have intermediate vertical slots and the container or body of the device has a partition received in said slots to divide the pockets of the assemblies into separate compartments, thus doubling the number of compartments without increasing the size or number of said assemblies.

A further object of this invention is to provide a filing device of the character referred to embodying novel identification carrying means for the pocket-forming cards or members of the assemblies.

The various objects and features of my invention will be fully understood from the following 15 detailed description of typical preferred forms and applications of my invention, throughout which description reference is made to the accompanying drawings, in which:

Fig. 1 is a perspective view of one form of device of this invention illustrating the manner in which the pocket providing assemblies may be spread apart at their upper ends. Fig. 2 is an enlarged perspective view of one of the elements for connecting the lower portions of the adjacent 20 boards or members providing the pockets of the assemblies. Fig. 3 is an enlarged fragmentary vertical detailed sectional view of the upper portion of one of the boards or members of the pocket assemblies illustrating the identification 25 means of the same. Fig. 4 is an enlarged fragmentary vertical detailed sectional view of the lower portion of one of the board members illustrating the manner in which the next board member is coupled with the same. Fig. 5 is a vertical 30 detailed sectional view of the device with portions of the foremost assembly broken away to illustrate the various parts. Fig. 6 is a vertical detailed sectional view of one of the pocket assemblies removed from the body. Fig. 7 is an enlarged fragmentary vertical detailed sectional 35 view of a portion of the body illustrating one of the sockets or slots for the hinge lug of one of the hinged dividers and Fig. 8 is a view similar to Fig. 5 illustrating another embodiment of the 40 invention.

The form of the invention illustrated in Figs. 1 to 7, inclusive, may be said to comprise, generally, a body 10, a plurality of pocket providing assemblies 11 in the body 10 and means 12 for spreading the upper portions of said assemblies 11.

The body 10 serves to receive the several assemblies 11 and to carry the other elements of the device. In the preferred construction the body 10 is a simple elongate rectangular structure comprising spaced sides 13 and ends 14. The

sides 13 are vertical members provided at their upper and lower edges with inturned flanges 15 and 16, respectively. Vertical flanges or aprons 17 extend upwardly from the inner edges of the lower flanges 16. It will be observed that the body sides 13 are simple one-piece members which may be inexpensively formed of sheet metal, or the like. The upper flanges 15 of the sides 13 carry rails 18. The rails 18 are provided with flanges 19 which lie against the outer surfaces of the sides 13 and the rails carry depending flanges or aprons 20 which are vertical and lie in the same plane as the aprons 17. The rails 18 are shaped to have raised ridges 21. The ridges 21 are spaced between the opposite longitudinal edges of the rails 18 and preferably extend along the rails from one end to the other. In the preferred construction the ridges 21 are of inverted V-shape in vertical cross section. The rails 18 are plated or otherwise finished so that their exposed surfaces are smooth. The functions of the rails 18 and their ridges 21 will be later described.

The ends 14 of the body 10 may be simple vertical members having inturned flanges 22 at their opposite edges welded or otherwise fixed to the sides 13. Similar flanges 23 may be provided along the lower edges of the ends 14 and may be suitably fixed to the bottom flanges 16 of the sides 13. Outturned lips or rims 24 extend along the upper edges of the ends 14 and may be employed as grips or handles to facilitate the use of the device. The bottom of the body 10 may be open.

The assemblies 11 are removably inserted in the body 10 and serve to hold the documents, cards or papers. There is usually a plurality of assemblies 11 and in accordance with the invention the individual assemblies may be increased or decreased in extent as required. The several assemblies 11 are alike and each includes a plurality of sheets, cards, plates or boards which I will term members 25. The members 25 are generally rectangular elements formed of fiber board, cardboard, stiff paper, or the like. It is usually preferred to provide members 25 with straight horizontal upper and lower edges. The side edges of the members 25 are stepped, the members being reduced in width at their lower portions to have downwardly facing horizontal shoulders 26 at their opposite side edges. The shoulders 26 of any given member 25 occur in a common horizontal plane and rest on the rails 18 to support the member in the body 10. V notches 27 are formed in the shoulders 26 to receive or cooperate with the ridges 21. The cooperation of the notches 27 with the ridges 21 guides the members 25 and the assemblies 11 and prevents the members from assuming diagonal positions where they may fall or catch between the aprons 20. In accordance with the invention the shoulders 26 are in stepped relation, the shoulders of the several members 25 of each assembly 11 being in a downwardly and rearwardly stepped progression prior to the connection or assembly of the members. Thus, in each assembly 11, the shoulders 26 of the front member 25 may be adjacent the top of the member, the shoulders of the second to the foremost member 25 are somewhat lower, the shoulders 26 of the third to the foremost member being still lower and so on. The members 25 are connected or assembled by means to be later described so that their shoulders 26 occur in a common horizontal plane to all rest on the rails 18. When the vertically stepped shoulders 26 are brought to a common plane the members 25 are stepped upwardly and rearwardly, the upper end

of the second to the foremost member 25 being above the front member, the upper edge of the third to the foremost member being above the second to the foremost member and so on. This upward and rearward stepped progression of the members 25 is clearly illustrated in Figs. 1, 5 and 6 of the drawings. The vertical stepping of the members 25 is sufficient to leave clear or exposed spaces at the upper edges of the members of sufficient vertical width or extent to carry the required identification and to facilitate the easy manipulation of the members. The members 25 are initially engaged in close relation one in front of the other but are capable of being spread apart to permit the insertion and removal of the papers, and the addition of the ledger sheets, charge slips, or the like, to the file may spread the members 25 apart.

The assemblies 11 include novel and particularly effective means for coupling or connecting the lower parts of the members 25 to retain the members in the stepped relation above described where their shoulders 26 are in a common horizontal plane to rest on the rails 18. These means are such that members 25 may be added to and removed from the assemblies 11 as conditions may require and are such that the members 25 may be freely swung or hinged forwardly to give free access to the pockets or paper containing spaces between the adjacent members.

The means for connecting the adjacent members 25 comprise clips or hinge parts 28 attached to the lower edge portions of the members. Figs. 2 and 4 of the drawings illustrate the clip or hinge parts 28 in detail. There may be a single hinge part 28 for each member 25 but where the members 25 are of substantial width I prefer to provide two or more parts 28 for each member. The parts 28 may be formed of sheet metal, or the like, and are elongate members adapted to lie flat against the rear sides of their respective members 25. Forwardly projecting prongs 29 extend from the upper edges of the members 28 adjacent their opposite ends. The prongs 29 are pointed or have convergent edges. The prongs 29 are passed forwardly through openings in their respective members 25 and are then turned or bent downwardly and rearwardly to engage against the forward faces of the members 25. This secures the hinged parts 28 to the members 25.

The hinge parts 28 are proportioned to have their lower edge portions extend downwardly beyond the lower edges of their respective members 25. Elongate horizontal slots 30 are provided in these downwardly projecting edge portions of the hinge parts 28. The upper walls of the slots 30 preferably occur in the same planes as the lower edges of the members 25. The parts 28 further include rearwardly projecting generally horizontal flanges 31. There is preferably a single flange 31 extending rearwardly from the upper edge of each hinge part 28. It is preferred to make the flanges 31 of substantial length and in practice the flanges may extend between the spaced prongs 29. A down turned lip 32 extends along the rear edge of each flange 31. The lips 32 are generally vertical and substantially parallel with their respective hinge parts 28. The flanges 31 and their lips 32 are slightly shorter than the slots 30.

The flanges 31 and the lips 32 are designed to be received in the slots of the hinge part 28 on the adjacent members 25. Fig. 4 of the drawings illustrates the manner in which two members 24 are hingedly connected by interengaging their

respective hinge parts 28. The member 25 being added to the assembly is first arranged in a generally horizontal position and is then raised so that its slot 30 receives the lip 32 of the vertical member 25. The member 25 being added is then raised to bring its part 28 to the flange 31 of the vertical member 25 and is then swung upwardly and forwardly to a vertical position such as is shown in section in Fig. 6. This engages the slotted lower portion of the added member 25 on the flange 31 of the first member 25 and latches the two members 25 together. The cooperation of the slot 30 with the flange 31 supports the rear member 25 on the hinge part 28 of the other member 25 so that it is stepped above said other member, the extent of this vertical offsetting or stepping being determined by the proportions of the hinge parts 28.

It will be noted that each of the members 25 except the rearmost one of the series is supported from the next adjacent member to the rear by the cooperation of the hinge members 28. Accordingly, the assembled series may be supported from the shoulders 26 of one of the cards, preferably the rearmost, if desired. Under such conditions the shoulders 26 may be omitted from some or all of the remaining cards.

The several hinge parts 28 of the assemblies 11 are preferably identical so that the vertical stepping of the members 25 is uniform. The lower edges of the members 25 may bear on the flanges 31 of the preceding members 25 to relieve the hinge parts 28 of a portion of the load. The slots 30 receive the flanges 31 with clearance to allow free relative pivoting or swinging of the members 25. It will be observed that the flanges 31 form shelves or bottoms, for the paper receiving compartments occurring between the members 25, to support the ledger sheets or other papers. As the contents of the assemblies 11 increase the hinge parts 28 move rearwardly on their respective flanges 31 to accommodate the filed papers. Additional members 25 may be easily added to the assemblies 11 and, if desired, the assemblies 11 may be reduced in extent by removing the members 11 from their front or rear sides. The clip or hinge parts 28 may be provided as separate elements to be applied to the members 25 as required or the members 25 may be already equipped with the hinge parts 28.

The elements or members 25 of the assemblies 11 are provided with novel and very effective identification means. These identification means include strips 33 of transparent material, such as Celluloid, or the like, extending along the upper edges of the members 25. The strips 33 are preferably channel shaped in transverse cross section to have aprons or flanges depending across the front and rear surfaces of the members 25. The strips 33 may extend substantially the entire lengths of the top edges of the members 25. Wire staples 34 or the like, secure the strips 33 to the members 25 adjacent the ends of the strips. The strips 33 may be relatively stiff but the securing of the strips to the members 25 at widely spaced points permits a limited play or movement of the forward flanges of the strips when the same are intentionally manipulated. Tabs 35 are struck forwardly from the material of the members 25. The tabs 35 are spaced below the strips 33 and occur in common horizontal planes on their respective members 25. As best illustrated in Fig. 3 of the drawings, the tabs 35 lie substantially parallel with and adjacent to the forward faces of their members 25. There may be several tabs 35 spaced across the face of each member 25.

Paper or card slips 36 bearing or adapted to bear the required identifications for the several members 25 are entered upwardly under the transparent forward strips 33 and are engaged downwardly behind the tabs 35. It will be apparent how the cards or paper slips 36 may be readily arranged in place and removed as required. The transparent slips 33 are effective in retaining and protecting the identification slips. The members 25 may be rapidly handled and manipulated without soiling, tearing or injuring the identification slips 36 and the transparent strips 33 protect both the identification slips 36 and the upper edge portions of the members 25.

The means 12 are important features of the invention. The means 12 are operable to spread forwardly the upper portions of the several assemblies 11 to make the assemblies and their respective members 25 readily visible and easily accessible. The means 12 includes a plurality of hinged or pivoted plates 37 arranged in the body 10 at longitudinally spaced points. The plates 37 may be spaced along the body 10 as operating conditions may require and serve as dividers to separate the multiplicity of assemblies 11 into separate groups of assemblies. The plates 37 are formed of sheet metal, stiff fiber board, or other material having considerable rigidity.

As illustrated in the drawings, the plates 37 are of substantially the same configuration as the above described members 25, being generally rectangular elements reduced in width at their lower portions to enter the body 10 and to have downwardly facing horizontal shoulders 38. The shoulders 38 are adapted to rest on the rails 18 when the plates 37 are in inclined positions as will be more fully described. V-shaped notches 39 are formed in the shoulders 38 to receive or cooperate with the ridges 21. The lower portions of the plates 37 are received between the spaced opposed pairs of aprons 17 and 20 with suitable working clearance. It is preferred to proportion the plates 37 so that their upper edges are in about the same plane as the upper edges of the rearmost members 25 of the assemblies 11 and the upper exposed parts of the plates 37 may be slightly wider than the members 25.

The invention provides novel and effective means for removably pivotally mounting the plates in the body 10 to hinge or swing about horizontal axes spaced above their lower ends. The aprons 17 are provided with longitudinally spaced slots 40 extending downwardly from their upper edges. The slots 40 of the two aprons 17 are directly opposite, that is, they occur in pairs, and the slots 40 may be equally spaced throughout the lengths of the aprons. The slots 40 slope downwardly and rearwardly from the upper edges of the aprons 17 and are widened or enlarged at their lower ends to have pockets 41. The pockets 41 are generally V-shaped or keystone-shaped having downwardly convergent forward and rear walls and flat generally horizontal upper and lower walls. The means for hingedly or pivotally mounting the plates 37 further include trunnions or pivot lugs 42 projecting from the opposite side edges of the plates. The lugs 42 are adapted to be passed downwardly through the slots 40 to the pockets 41 and are adapted to bear in the pockets 41 to pivotally support their respective plates 37. It will be seen how the plates 37 may be brought to forwardly and upwardly inclined positions with their lugs 42 at the mouths of the slots 40 and then lowered to bring the lugs into the pockets 41. The lugs 42 bear on the lower walls of the

pockets and are adapted to swing forwardly and rearwardly in the pockets when the plates 37 are hinged or swung. The sloping walls of the pockets 41 limit the extent of forward and rearward pivoting of the plates 37, the flat sides of the lugs 42 engaging with the walls of the pockets 41 to stop or limit pivoting of the plates. It is to be observed that where the slots 40 are spaced along the aprons 17 the divider plates 37 may be arranged at selected points throughout the length of the body 10 to divide the series of assemblies 11 into as many sub-groups as required with the sub-groups of any selected extents.

The means 12 further include what I will term pusher plates 43. The pusher plates 43 are arranged immediately in front of the divider plates 37, there being a pusher plate 43 provided for each divider plate. The pusher plates 43 are generally rectangular members of substantially the same proportions and shape as their respective divider plates 37 and are provided at their opposite edges with downwardly facing horizontal shoulders 44 adapted to cooperate with the rails 18. The shoulders 44 are notched to cooperate with or receive the ridges 21. The pusher plates 43 are preferably formed of relatively stiff but somewhat flexible and resilient material such as sheet metal, stiff fiber board, or the like. It is preferred to merely removably insert the pusher plates 43 immediately in front of each divider plate 37. The pusher plates 43 may be of substantially the same size as the divider plates 37 or may be somewhat longer to extend downwardly between the lower edges of the plates 37. The divider plates 37 and the pusher plates 43 are both entirely clear of the bottom of the body 10 and the support on which the body is resting. The pusher plates 43 may be provided at their upper edges with window tabs 47 whose windows may carry identification cards or sheets 47a. If desired, the identification tabs 47 may be provided on the hinged divider plates 37 instead of the pusher plates 43. As above mentioned, the pusher plates 43 are free or unsecured.

When an adjacent divider plate 37 is tilted to the forward position the respective pusher plate 43 may likewise be tilted forwardly and then shoved or pushed downwardly and rearwardly. This brings the lower edge of the pusher plate against the front of the foremost assembly 11. The pusher plate 43 pushes rearwardly against the assembly 11 adjacent its lower edge and the operator may apply a substantial rearward and downward force against the pusher plate to compress or shift rearwardly the lower portions of the assemblies 11. As the assemblies 11 are supported between their upper and lower ends on the rails 18 rearward force against their lower parts causes the upper parts to swing forwardly and thus separate one from the other. Fig. 1 of the drawings illustrates the manner in which a pusher plate 43 may be shoved rearwardly against the lower part of the adjacent assembly 11 to spread the upper parts of the assemblies. In practice, the pusher plates 43 may be formed of flexible resilient material and when forced downwardly and rearwardly as just described, they may flex to some extent. When the pusher plates are brought to forwardly inclined positions their shoulders 44 ride along the rails 18. This engagement prevents the pusher plates from being shoved directly downward and the shoulders 44 engaging on the rails 18 pivotally or swingably support the pusher plates so that their rear parts may swing rearwardly against the assemblies 11.

Fig. 8 of the drawings illustrates an alternative or modified form of the invention in which the body 10 is partitioned and the assemblies 11a are constructed so that their paper receiving pockets are divided. A vertical partition 50 extends longitudinally through the body 10 from its front end 14 to its rear end 14. There may be one or more such partitions 50. The partition 50 may be a sheet of metal, or the like, bent longitudinally to have spaced parallel cheeks or side parts and to have a rounded upper edge 51. The partition 50 may be of substantially the same height as the body sides 13. The paper receiving assemblies 11a are substantially the same as the assemblies 11 described above but are formed to cooperate with or receive the partition 50. The members 25a of the assemblies 11a have vertical slots 52 extending upwardly from their lower edges to receive the partition 50. The slots 52 are proportioned to receive the partition 50 with suitable clearance. The partition 50, passing through the several slots 52, partitions or divides each of the paper receiving spaces of the assemblies 11a into individual pockets or spaces. Separate identification means is preferably provided for each paper receiving pocket or space of the assemblies 11. The identification means may be substantially the same as described above comprising transparent edge strips 33a, retaining tabs 35a and the identification cards or slips 36a. Where the spaces between the adjacent members 25a are partitioned or divided by the partition 50 each member 25a carries two sets of strips 33a, tabs 35a and identification slips 36a.

It is believed that the utility and practicability of the filing device provided by this invention will be readily understood from the foregoing detailed description. Referring to the structure illustrated in Figs. 1 to 7, inclusive, the body 10 may be provided with as many assemblies 11 as required and the assemblies may embody as many members 25 as needed. As above described, the assemblies 11 may be readily enlarged in capacity by the addition of additional members 25 and may be reduced in size by the simple removal of the unneeded members 25. The clip or hinge parts 28 provide for the ready addition of members 25 to the assemblies 11 and are such that the unnecessary members 25 may be quickly disengaged and removed. The pockets or spaces between the adjacent members 25 are adapted to readily receive the ledger sheets, charge sheets, etc. and the flanges 31 of the hinge parts 28 may be proportioned so that these paper receiving spaces have a substantial capacity. It is to be observed that the papers are retained in a flat state by reason of being engaged between the spaced generally parallel members 25. When it is desired to remove papers, sort in papers or inspect papers in a given assembly 11 or a given group of assemblies 11, the divider plate 37 and the pusher plate 43 in front of that group of assemblies 11 are swung to the forwardly and upwardly projecting positions. When this is done the lower portion of the plate 37 swings rearwardly and may engage the adjacent pusher plate 43 to assist in shifting the same rearwardly at its lower end. The lugs 42 of the plate 37 engage against the forward walls of their pockets 41 to limit the forward shifting of the plate. The pusher plate 43 is then pushed downwardly and rearwardly, that is, a downward and rearward force applied to its upper part. This causes the lower portion of the member to move rearwardly against the foremost assembly 11. The shoulders 44 of the pusher

plate 43 may slide along or may be slid along the rails 18 when the plate is forced downwardly. The rearward force exerted on the lower portions of the assemblies 11 by the lower edge part of the pusher plate 43 compacts the lower portions of the assemblies causing them to move rearwardly. The assemblies are pivotally supported on the rails 18 by their shoulders 38 and the rearward movement of the lower parts of the assemblies 11 is accompanied by forward movement of the upper parts of the assemblies. Thus, the upper parts of the assemblies are spread apart. This exposes the upper portions of the several members 25 and makes the members and their paper receiving spaces readily visible and accessible. The upwardly and rearwardly stepped progression of the members 25 materially facilitates the expeditious sorting and withdrawal of papers. The user merely runs his hand or fingers rearwardly along the upper parts of an assembly 11 until he reaches the desired paper receiving space and this space is readily opened or widened for the sorting in of the paper, withdrawal of the papers, or the like. When the filing is completed the divider plate 37 and the pusher plate 43 may be swung back to their normal upwardly and rearwardly sloping positions to restore the members 25 to their compact normal relation.

Having described typical preferred forms and applications of my invention, I do not wish to be limited or restricted to the specific details herein set forth, but wish to reserve to myself any variations or modifications that may appear to those skilled in the art and fall within the scope of the following claims.

Having described my invention, I claim:

1. A filing device comprising, in combination, a group of flat sheets assembled face-to-face in vertically stepped relation, hinge means connecting adjacent sheets at their lower edges to hold said sheets in said vertically stepped relation and to form a series of vertically opening file pockets, said hinge means having a slideable connection to provide for transverse shifting of one sheet toward and away from the adjacent sheets to expand or contract the pockets formed by the sheets, said hinge means providing for pivoting of adjacent sheets about a horizontal axis extending laterally of the sheets but preventing vertical movement of adjacent sheets relative to each other, and means on at least one of said sheets for supporting the assembled group of sheets.

2. A filing device comprising, in combination, a group of flat sheets assembled face-to-face in vertically stepped relation, similar hinge members adjacent the lower edge of each sheet, the hinge member of one sheet interengaging with the hinge members of the adjacent sheets in front of and in back of said one sheet to interconnect the sheets to hold said sheets in said vertical stepped relation and prevent vertical movement of said sheets relative to each other and thereby form vertically opening file pockets, said interengaging hinge members having a sliding connec-

tion to provide for adjusting the thickness of said pockets, and means on at least one of said sheets for suspending an assembled group of sheets.

3. A filing device comprising, in combination, 5 a group of flat sheets assembled face-to-face in vertically stepped relation, similar connecting members on said sheets each having a first part projecting below the lower edge of the sheet and a second part spaced upwardly from said lower edge and projecting rearwardly of the sheet, the first part of one member interfitting with the second part of the adjacent member to connect the associated sheets and thereby form upwardly opening file pockets, said first and second parts 10 when interfitted holding said sheets against vertical movement relative to each other and in said vertically stepped relation and being readily shiftable transversely of the plane of the sheets to adjust the thickness of the pocket formed by the sheets.
4. A filing device comprising, in combination, 15 a group of flat sheets assembled face-to-face in vertically stepped relation, connecting members secured to the lower edges of each sheet, each of 20 said members having an edge portion projecting beyond the lower edge of the associated sheet and a rearwardly projecting flange, the lower edge portion of each member having an elongated slot 25 adapted to receive the flange of the connecting member on the next adjacent sheet in front whereby the sheets are disengageably interconnected to form vertically opening pockets, said flanges holding said sheets against vertical movement relative to each other and in said vertically 30 stepped relation and being adjustable in said slots to vary the thickness of the pockets formed by the adjacent sheets.
